UNITED STATES PATENT OFFICE.

MILO A. BAKER, HERBERT U. DURANT, AND SAMUEL U. KING, OF LOS ANGELES,
CALIFORNIA.

SAFETY DEVICE FOR HIGH-SPEED ELEVATORS.

Application filed September 24, 1923. Serial No. 664,436.

To all whom it may concern:

Be it known that we, MILO A. BAKER, HERBERT U. DURANT, and SAMUEL U. KING, citizens of the United States, residing at

5 Los Angeles, in the county of Los Angeles and State of California, have invented a new and useful Safety Device for High-Speed Elevators, of which the following is a specification.

10 This invention relates to safety devices of the type employed on high speed elevators for preventing falling of the elevator platform or cab in event of the suspension cables breaking.

15 An object of the invention is to effect gradual stoppage of the falling elevator platform within a comparatively short distance without shock.

In safety devices of this type of prior construction, a relatively great period of time elapses before engagement of the friction shoes with the elevator guides occurs, and, consequently, the elevator platform falls a considerable distance before the slowing up 25 or braking action on the platform begins.

A further object of this invention is to begin frictional retardation of the falling elevator platform when the platform has dropped but a comparatively short distance 30 and to then gradually and more slowly increase the friction so as to bring the elevator to a full stop very shortly thereafter.

A further object is to provide a device of this character of comparatively simple 35 construction so that there will be very little likelihood of it getting out of order.

The accompanying drawings illustrate the invention:

Figure 1 is a broken side elevation of a 40 safety device constructed in accordance with the provisions of this invention, the same being shown attached to the elevator platform beams and the elevator guides being omitted in this view.

45 Fig. 2 is an inverted plan section on line 2—2 of Figure 1, the elevator guides being shown in place.

Fig. 3 is an end view of Figure 2, omitting the guides.

50 Fig. 4 is an enlarged fragmental plan, partly in section, from the line indicated by 4—4, Figure 1.

Fig. 5 is an end view of Figure 4 from the left thereof.

55 Fig. 6 is a plan view similar to Fig. 4,

but showing less of the shoe-operating arms, and the drum shaft is turned sufficiently to disengage the clutch and cause the rollers to ride upon the wedge sleeve.

Fig. 7 is a fragmental end view of Figure 6 from the left thereof, the position of the wedge sleeve corresponding to that shown in Fig. 4.

Fig. 8 is a sectional elevation on the line indicated by 8—8, Figure 6.

A governor-controlled drum is indicated at 11. The governor and cable that serve to set this drum into operation are not illustrated or described herein since their construction and operation are well understood in the art relating to elevator safety devices.

It suffices to state that the governor is adjusted so that if the elevator platform attains a dangerous speed in descending, as, for example, in case the suspension cables break, the governor operates to cause a cable, not shown, wound on the drum 11 to be held stationary and thus turn said drum in the direction of the arrow *a* in

75 Figure 1. The drum 11 is mounted on a shaft 12 having screw-threads 13 at its opposite ends, the screw threads being the reverse of each other, that is to say, those at one end being left hand and those at

70 the other right hand. The bearings of the shaft 12 are indicated at 14 and are formed in a yoke 15 which is bolted to the under

75 face of a pair of platform beams 16. The foregoing described construction is well

80 understood in this art.

85 Means are provided to press a shoe against one of the elevator guides and, in this instance, said means are operated comparatively fast by turning of the shaft 12

90 less than one revolution in one direction to engage the shoe with the guide and operated at a slower rate by further turning of the shaft to more and more forcibly engage

95 the guide. These means may be variously constructed and the invention in its broader

100 phases is not limited to the particular means illustrated. The construction of said means, now to be described, is provided in duplicate at opposite ends of the shaft 12 and, consequently, it will be necessary to describe

105 only that at one end. The screw threads 13 engage a threaded nut 17 which provides at one end a female clutch member 18 adapted to be engaged by a male clutch

110 member 19 fixed by a pin 20, or its equiva-

lent, to the drum shaft so as to be turned by said shaft. During the normal operation of the elevator the clutch members 18, 19 will be in engagement as in Figure 4 5 so that turning of the drum will rotate the nut.

The nut 17 is free to turn in a wedge sleeve 21, said sleeve being held against longitudinal movement relative to the nut 10 by a suitable locking pin 22, or its equivalent. The wedge sleeve 21 is provided with longitudinally extending slots 23, the bottom walls 24 of said slots being aslant toward the axis of the drum shaft in a direction 15 leading away from the clutch members or, in other words, toward a pair of rollers 25 which are sufficiently narrow to enter the slots 23. The rollers 25 are rotatably mounted on shafts 26 which are supported, 20 respectively, in pivotally mounted levers 27. Each of the shafts 26 projects sufficiently beyond the levers 27 to engage the hook-shape ends 28 of a coil spring or springs 29 which, consequently, tend to hold the 25 rollers 25 normally in contact with flattened or cam faces 30 of the nut 17, these faces 30 being contiguous to the portion 31 upon which the wedge sleeve 21 is mounted.

The pivots for the arms 27 are indicated 30 at 33 and are mounted in a member 34 that is bolted to the underface of the beams 16.

Pivoted at 35 to the levers 27 is the shoe or shoes previously referred to and these shoes are indicated at 36 and are arranged 35 on opposite sides of one of the elevator guides 37 so that when the rollers 25 are thrust outwardly by the wedge sleeve 21, the shoes 36 will be caused to frictionally engage the guide 37. The parts just described are proportioned so that frictional gripping of the guide by the shoes 36 takes place when the rollers 25 have ridden off of the cam faces 30, as in Figure 6. Resuming the description of the means operating the shoes, the nut 17 is provided at 40 its periphery with a pair of shoulders 38, 39, the shoulder 38 being adapted to be brought into engagement with a shoulder 40 on the wedge sleeve 21 when the nut 50 is turned in the direction indicated by the arrow *b* in Figure 8, and the shoulder 39 being adapted to engage a shoulder 41 on the wedge sleeve 21 when the nut is turned in a direction opposite to that indicated by the arrow *b*, or in the direction of the arrow *a*, Figure 1.

The invention above described operates, as follows:

Assuming that the parts are in the positions 60 in which they are shown in Figures 4 and 5 of the drawings and that the elevator suspension cables have broken, permitting the elevator platform to drop at a dangerous speed, the drum 11 will be caused 65 to rotate in the direction of the arrow *a*

because of the operation of the elevator governor at a speed higher than that at which the safety device is to remain inactive, in a manner well understood in this art, thus rotating the shaft 12 in the direction of the arrow *c*, Figures 5, 7 and 8. This rotation of the shaft rotates the clutch 18, 19, thus rotating the nut and causing the rollers 25 to ride off of the cam faces 30 onto the higher cam faces 32, operating 70 the levers 27 to cause the shoes 36 to operate comparatively fast to frictionally grip the elevator guide 37. This rotation of the clutch also causes the shoulder 39 to engage the shoulder 41. This occurs in less than 75 a quarter of a turn of the shaft 12, and causes the nut 17 to be held against further rotation and, in consequence, said nut is translated from the position shown in Fig. 4, to the left thus disengaging the clutch members and causing the slanting slot walls 24 to wedgedly move the rollers 25 away from each other and thus to gradually contract the shoes 36 at a slower rate upon the elevator guide 37, until the friction between 80 said shoes and guide becomes so great as to bring the elevator to a stop. Thus, it will be seen that there are provided means to first effect relatively quick contraction of the shoes 36 upon the guide 37 and thereafter relatively slow contraction of said shoes upon the guide. By these means the shoes are moved from position giving ample clearance between them and the guide to a gripping position within a period of time 85 in which the drum shaft makes less than one revolution or, in this instance, only about one-quarter of a revolution. This enables a falling elevator to be gradually stopped within a distance that is less than 90 that between two floors of a building.

The guide-blocks, shown at 42, are of the usual type employed on the elevator platform for engaging the guides 37 and, therefore, need not be described in detail herein.

It will be readily understood from the foregoing description that the nut 17 constitutes a member mounted for rotation and translation, that the cam face 30 operates upon rotation of said member, that the slanting face 21 constitutes a cam face for the nut operating upon translation of said member, that the rollers 25 constitute one form of follower which may be otherwise constructed, and that the drum 11, shaft 12, screw threads 13, clutch 18, 19 with the shoulders 39, 41 constitute means operable to alternately rotate and translate said member.

We claim:

1. A safety device of the character described comprising a shaft, a shoe, and means operated comparatively fast by turning of the shaft less than one revolution in one direction to press the shoe against an 130

elevator guide and operated at a slower rate by further turning of the shaft to more and more forcibly engage the guide.

2. A safety device of the character described comprising a shaft having screw threads, a nut engaging the screw threads, means operated by the shaft to releasably engage and rotate the nut, means to hold the nut against rotation after it has been 10 rotated through a certain number of degrees of circular measurement, a shoe, and means operated by the rotation of the nut and thereafter by translation of the nut to move the shoe toward an elevator guide.

3. A safety device of the character described comprising a member mounted for rotation and translation and provided with a rotative operated cam face and with a translation operated cam face, a shoe, a follower operably connected with the shoe 20 and successively engaged by the respective cam faces, and means operable to alternatively rotate and translate said member.

Signed at Los Angeles, Calif., this 17th day of September 1923.
